CLAIM

The ornamental design for an auto seat belt buckle boot,
as shown and described.

DESCRIPTION

[22] Filed: Sep. 26, 1986

FIG. 1 is a bottom perspective view of an auto seat belt
buckle boot showing our new design;
FIG. 2 is a front elevational view;
FIG. 3 is a right side elevational view; and
FIG. 4 is a view of the boot unfolded.
